(57) **CLAIM**

The ornamental design for a speaker shelf, as shown and described.

DESCRIPTION

FIG. 1 is a perspective view of a speaker shelf, according to a first embodiment of the invention.

FIG. 2 is another perspective view of the first embodiment.

FIG. 3 is a front elevation view of the first embodiment.

FIG. 4 is a rear elevation view of the first embodiment.

FIG. 5 is a side view of the first embodiment.

FIG. 6 is an opposite side view of the first embodiment.

FIG. 7 is a top plan view of the first embodiment.

FIG. 8 is a bottom plan view of the first embodiment.

FIG. 9 is a perspective view of a speaker shelf, according to a second embodiment of the invention.

FIG. 10 is another perspective view of the second embodiment.

FIG. 11 is a front elevation view of the second embodiment.

FIG. 12 is a rear elevation view of the second embodiment.

FIG. 13 is a side view of the second embodiment.

FIG. 14 is an opposite side view of the second embodiment.

FIG. 15 is a top plan view of the second embodiment.

FIG. 16 is a bottom plan view of the second embodiment.

FIG. 17 is a perspective view of a speaker shelf, according to a third embodiment of the invention.

FIG. 18 is another perspective view of the third embodiment.

FIG. 19 is a front elevation view of the third embodiment.

FIG. 20 is a rear elevation view of the third embodiment.

FIG. 21 is a side view of the third embodiment.

FIG. 22 is an opposite side view of the third embodiment.

FIG. 23 is a top plan view of the third embodiment.

FIG. 24 is a bottom plan view of the third embodiment.

FIG. 25 is a perspective view of a speaker shelf, according to a fourth embodiment of the invention.

FIG. 26 is another perspective view of the fourth embodiment.

FIG. 27 is a front elevation view of the fourth embodiment.

FIG. 28 is a rear elevation view of the fourth embodiment.

(Continued)

FIG. 29 is a side view of the fourth embodiment.
 FIG. 30 is an opposite side view of the fourth embodiment.
 FIG. 31 is a top plan view of the fourth embodiment.
 FIG. 32 is a bottom plan view of the fourth embodiment.
 FIG. 33 is a perspective view of a speaker shelf, according to a fifth embodiment of the invention.
 FIG. 34 is another perspective view of the fifth embodiment.
 FIG. 35 is a front elevation view of the fifth embodiment.
 FIG. 36 is a rear elevation view of the fifth embodiment.
 FIG. 37 is a side view of the fifth embodiment.
 FIG. 38 is an opposite side view of the fifth embodiment.
 FIG. 39 is a top plan view of the fifth embodiment; and,
 FIG. 40 is a bottom plan view of the fifth embodiment.
 The broken lines shown in the figures represent portions of the speaker shelf that form no part of the claimed design.
